UNITED STATES PATENT OFFICE.

LAWRENCE BURZYNSKI, OF BENTON, ILLINOIS, ASSIGNOR OF ONE-HALF TO J. M. SEYMOUR, OF BENTON, ILLINOIS.

IRONING MACHINE.

Application filed May 25, 1923. Serial No. 641,416.

To all whom it may concern:

Be it known that I, LAWRENCE BURZYNSKI, a citizen of the United States of America, residing at Benton, in the county of Franklin and State of Illinois, have invented certain new and useful Improvements in Ironing Machines, of which the following is a specification.

This invention relates to certain new and useful improvements in ironing machines and has particular reference to a motor operated reciprocable frame resiliently supporting an electrically heated iron above an ironing board.

15 The primary object of the invention embodies in an ironing machine of the above type, an ironing board having a rack frame reciprocably mounted thereabove with a motor operating a gear and clutch devices associated with the rack frame to reciprocate the latter, the clutch devices being operable when the rack frame reaches its limit of movement in opposite directions for reversing the direction of movement of the rack

25 frame.

The invention further embodies a reciprocating carriage for an electrically heated or sadiron, with spring devices associated with the carriage and iron for normally holding the iron in an elevated position above an ironing board.

With the above general objects in view and others that will appear as the nature of the invention is better understood, the same 35 consists in the novel construction, combination and arrangement of parts hereinafter more fully described, illustrated in the accompanying drawings, and pointed out in the appended claims.

40 In the drawings forming a part of this application and in which like designating characters refer to corresponding parts throughout the several views:

Figure 1 is a top plan view of an ironing 45 machine constructed in accordance with the present invention, showing the ironing board, the rack frame reciprocably mounted thereon and resiliently supporting an iron, and the motor and gear train for operating the rack frame,

Figure 2 is a longitudinal sectional view taken on line II-II of Figure 1 showing the worm on the motor shaft for operating

gear train and the resilient mounting of the iron,

55 Figure 3 is a detail sectional view taken on line III-III of Figure 1 showing the gearing at one side of the machine for reciprocating the rack frame,

Figure 4 is a detail sectional view taken 60 on line IV-IV of Figure 1,

Figure 5 is a fragmentary side elevational view of the machine, showing by dotted lines the train of gearing of the opposite side of the machine with the idler gear for 65 reversing the direction of movement of the rack frame,

Figure 6 is a detail sectional view taken on line VI-VI of Figure 1,

70 Figure 7 is a cross sectional view taken on line VII-VII of Figure 1 showing the resilient mounting for the iron with the ironing board spaced below the same,

Figure 8 is a fragmentary side elevational view showing a bayonet slot construction 75 for holding the iron in an elevated position.

Referring more in detail to the accompanying drawings, there is illustrated an ironing board 1 mounted upon hinged legs 2 that may be braced in any suitable manner, the legs preferably being folded to assume a position adjacent the under side of the board 1 when out of use. To accommodate the reciprocal mounting of an iron above the board 1, the latter adjacent one end thereof is provided with side walls 3 carrying forwardly directed guide arms 4, the upper edges of the side walls 3 and guide arms 4 being rabbeted with a series of anti-friction roller bearings 5 journaled in the rabbeted portion.

85 A pair of rack bars 6 are longitudinally slidable in the rabbeted portion of the side walls 3 and guide arms 4, the same being 90 connected at their forward ends shown in Figures 1, 2, and 7 by U-shaped straps having horizontal cross arms 7 and vertical side legs 8, the legs 8 being slotted as at 9 to 95 slidably receive the inwardly directed pins 10, carried by the rack bars 6. As shown, an electrically heated iron 11 is secured to the lower sides of the horizontal arms 7 of the U-shaped straps, and to maintain the iron 11 in an elevated position with respect to the ironing board 1, lateral brackets 12 100 are associated with the iron 11 with springs 105

13 connecting the outer ends of the brackets 12 to the rack bars 6 at points outwardly of said straps as clearly shown in Figure 7, pressure upon the handle of the iron 11 in 5 a downward direction, lowering the iron against the tension of the springs 13, for engagement with an article placed upon the ironing board 1, as will at once be obvious.

To effect reciprocating movement of the 10 rack bars, a motor and train of gearing driven thereby with clutch devices are associated with the rack bars 6, the motor 14 being mounted upon the ironing board 1 adjacent one end thereof between the side 15 walls 3 and having a shaft 15 operating a worm gear 16. A pair of standards 17 carried by the board 1 rotatably support a shaft 18 having a worm gear 19 fixed thereto midway the ends, in engagement with 20 the worm 16 as shown in Figures 1 and 4. Each end of the shaft 18 has a gear 20 journaled thereon, a clutch element 21 being formed integral with the inner face of each 25 of the gears 20. As shown more clearly in Figures 3, 4 and 5, side plates 22 and 23 are secured to the opposite side walls 3 and project upwardly of the rack bars 6, a shaft 24 being journaled in the upper ends 30 of the side plates 22 and 23 and supporting upon each end thereof the fixed double gear having a toothed portion 25 meshing with the teeth of the adjacent rack bar 6 and a smaller toothed portion 26 meshing with a gear 27 journaled in a bracket 28, the gear 35 27 being in mesh with the gear 20 upon the shaft 18. The reverse movement of the rack bar is effected by the interpositioning of an idler pinion 29 between the gears 20 and 26, the idler gear 29 being associated 40 with the gear train adjacent the side plate 23.

The devices for effecting reciprocation of the rack bars 6 include pairs of standards 30 supported by the board 1 at opposite 45 sides of the shafts 18 and 24 that slidably support at the upper ends thereof arms 31 and 32 having rollers 33 upon the oppositely projecting ends adjacent the rack bars 6, the arms 31 and 32 having fixed thereto 50 and slidable therewith cross braces 34 showing more clearly in Figures 1 and 4. The shaft 18 rotatably projects through the cross braces 34 and a clutch element 21^a having a hub portion 35 forming a bearing for 55 the cooperating cross brace 34 as clearly shown in Figure 4 is splined on each end of the shaft, the clutch element 21^a being movable upon the shaft 18 for cooperation with the selected clutch element 21 upon 60 movement of said cross braces. As shown in Figure 1, the inner faces of the rack bars 6 adjacent opposite ends thereof carry beveled blocks 31^a and 32^a for cooperation 65 with the sliding arms 31 and 32 respectively, shifting the arms and the clutch elements

movable therewith for reversing the direction of movement of the rack bars 6.

From the above detailed description of the device, it is believed that the construction and operation thereof will at once be apparent, it being noted that in connection with the iron 11, the same is of the electric type as illustrated and is resiliently supported upon the forward ends of the rack bars 6 normally to occupy a position elevated above the ironing board 1. When an article to be ironed has been placed upon the board, downward pressure of the handle of the iron will lower the same against the tension of the springs 13, and when pressure is relieved thereon, the iron will be automatically elevated to eliminate possibility of burning the article being ironed. The motor 14 operates the shaft 15 and worm 16 motion thereof being communicated by the worm gear 19 to the shaft 18 and to the desired clutch element 21^a. Assuming that the devices are coupled as illustrated in Figure 1, the gear train positively drives the gear 25 adjacent the side plate 22 for shifting the iron 11 in a direction over the board 1 toward the motor 14, the beveled block 31^a carried by the rack bar 6 at the proper time engaging the roller 33 to shift the arms 31 and 32 with the clutch elements 21^a carried thereby and placing into positive operation the opposite gear 25 adjacent the side plate 23, the interpositioning of the idler gear 29 as shown in Figures 1 and 5 effecting the reverse reciprocation of the rack bars 6. To relieve the strain upon the rack bar while it is being positively shifted, a shaft 36 as shown in Figures 1 to 5 is journaled in the rear ends of the side plates 22 and 23 and has fixed adjacent each end thereof a pinion 37 meshing with the teeth of the rack bars 6, providing for an even movement of the rack bars when only one of the gears 25 is positively shifting the adjacent rack bar. It will therefore be seen that when either of the bars 31 or 32 are shifted in the standard 30, the opposite clutch members are thrown into engagement to effect oppositely sliding movement of the rack bars 6, the idler gear 29 being provided to effect such reciprocation.

Another form of iron support is shown in Figure 8, the side legs 8^a of the U-shaped brackets supporting the iron 11, having bayonet-shaped slots 9^a formed therein to slidably receive the pins 10 carried by the rack bars 6. When it is desired to retain the iron 11 elevated with respect to the board 1, the iron is moved upwardly and then laterally shifted to position the pins 10 in the side portions of the lower ends of the slots 9^a.

While there are herein shown and described the preferred embodiment of the present invention, it is nevertheless to be

understood that minor changes may be made therein without departing from the spirit and scope of the invention as claimed.

Having thus described the invention, what

5 I claim as new is:—

1. In an ironing machine of the type described, a board, rack bars reciprocably mounted above the board, an iron resiliently supported by said rack bars and means for reciprocating the rack bars, said reciprocating means including a motor, a train of gearing interposed between the motor and the rack bars, said gearing train including two sets of gears each set cooperating with 10 a rack bar, a reversing gear associated with one of the gear sets, and a clutch device operable to move into alternative engagement with one or the other of the sets of gears.
- 20 2. In an ironing machine of the type described, a board, rack bars reciprocably mounted above the board, an iron resiliently supported by said rack bars and means for reciprocating the rack bars, said reciprocating means including a motor, a train of gearing interposed between the motor and the rack bars, said gearing train including two sets of gears each cooperating with a rack bar, a reversing gear associated with one of 25 the gear sets, a clutch device operable to move into alternative engagement with one or the other of the sets of gears, and cooperating means carried by the rack bars

and clutch devices for alternately placing the latter in operative position. 35

3. In an ironing machine of the type described, a board, rack bars reciprocably mounted above the board, an iron resiliently supported by said rack bars and means for reciprocating the rack bars, said reciprocating means including a motor, a train of gearing interposed between the motor and the rack bars, said gearing train including two sets of gears each cooperating with the rack bar, a reversing gear associated with one of the gear sets, a clutch device operable to move into alternative engagement with one or the other of the sets of gears, shiftably mounted arms connected to the clutch devices and a wedge block carried by each 40 rack bar adapted for alternate engagement with said arms for placing the clutch devices in their alternative opposite positions. 45

4. In an ironing machine of the type described, a board, rack bars reciprocably mounted above the board, an iron resiliently supported by said rack bars and means for reciprocating the rack bars, the mounting for the iron including U-shaped straps fixed to the iron and vertically slidable upon the 50 rack bars and springs connecting the iron to the rack bars for normally holding the same in a position elevated above the board. 55

In testimony whereof I affix my signature.

LAWRENCE BURZYNSKI.
